UNITED STATES PATENT OFFICE.

DAVID LARKIN, OF PITTSBURG, PENNSYLVANIA, ASSIGNOR TO HIMSELF, JOHN B. LARKIN, AND FRANK D. LARKIN, ALL OF SAME PLACE.

ROLLING-MILL FOR HOOP OR STRAP IRON.

SPECIFICATION forming part of Letters Patent No. 409,048, dated August 13, 1889.

Application filed April 5, 1889. Serial No. 306,122. (No model.)

To all whom it may concern:

Be it known that I, DAVID LARKIN, a citizen of the United States, residing at Pittsburg, in the county of Allegheny and State of Pennsylvania, have invented certain new and useful Improvements in Rolling-Mills for Strap, Hoop, or Band Metal; and I do hereby declare the following to be a full, clear, and exact description of the invention, reference being had 5 to the accompanying drawings, which form part of this specification.

My invention has relation to the manufacture of hoop, cotton-tie band, or other kinds or qualities of metal-work produced by the 15 reduction of the material from the billet to a long narrow and thin strip by passing through successive or a continuous train of reducing-rolls.

The object of my invention is to greatly 20 facilitate the reduction of the metal by obviating and overcoming the difficulties heretofore experienced in handling or working the material during its progress through the rolls and to thereby reduce the cost of production 25 as well as well as improve the texture of the finished product.

Heretofore, by reason of the frail texture, light gage, and semi-liquid condition of the metal during the process of reduction, it has 30 been impossible, without manual assistance and skillful manipulation, to effect a delivery of the end of the blank after emerging from one set of rolls to the slot or opening in the next set, while even after the delivery has 35 been accomplished the excess of material between the rolls, resulting from the elongation of the blank, buckles, vibrates, wraps, and sways about in a zigzag course, so as to become practically unmanageable, thus rendering 40 the manufacture of the grades of metal referred to impracticable with continuous rolls and necessitating the employment of hand-labor and the reduction of power and motion.

According to the method or process heretofore practiced for the reduction of metal from the billet to the long strip, band, or hoop blank the material has been passed alternately to and fro and from right to left or left to 50 right between a single pair of rolls or shifted

from one pair to the other. This operation is slow and tedious and subject to many difficulties, which need not be enumerated.

According to the object of my invention I purpose embracing a number of sets or trains 55 of rolls located at regular or irregular intervals of space with direct reference to the accommodation of the accumulation of or surplus metal that gathers between the rolls during the reduction and geared or interlocked 60 so as to feed the material with a continuous motion in one direction from the start to the finish.

My invention or improvement in the art of rolling or reducing the metal lies in the special 65 provision I have made to stiffen or brace the material during the intermediate stages of the process, so as to facilitate and insure its proper delivery from one set of rolls to the other. This provision consists in the construction of 70 a train of rolls for imparting to the blank a laterally-curved dished, dished and concaved, or corrugated shape, said train comprising two or more sets of intermediate rolls of the desired configuration, male and female, whereby 75 the surplus or accumulation between the rolls will be rendered sufficiently rigid and self-sustaining to prevent undue buckling, swaying, twisting, or distortion, and insure delivery from one set of rolls to the succeeding set, 80 the last set being so constructed as to reduce the dished, concave, or corrugated material to a flat surface, as required in finishing.

Incidental to the sets of rolls constituting a continuous train or mill and adapted to 85 conditions stated, I purpose using and arranging between the sets of rolls which impart to the stock a concave or dished form and maintain this shape a series of horizontal platforms, tables, planes, or guides, which may 90 be dished or curved to conform to the dish or curvature of the blank or corresponding female rolls, and which are adapted to assist by their guiding properties and positions the delivery of the metal from one set of rolls to 95 another, said platforms or planes constituting in effect a continuous track, guide, or conduit for the passage and guidance of the material from the starting to the final or finishing pass.

In the accompanying drawings, Figure 1 is a vertical longitudinal section of a rolling-mill or continuous train constructed and adapted for carrying my invention into effect. Fig. 2 is a front elevation of a set of rolls, respectively male and female, constructed and adapted to dish or concave the blank. Fig. 3 is a perspective view of a section of the blank having the dished or concave form. Fig. 4 is a similar view of a section of the finished stock or blank. Fig. 5 is a face view of the rolls for reducing the fin. Fig. 1 of the drawings shows five sets of rolls; but any suitable or convenient number may be employed.

15 The rolls are mounted in housings in the ordinary way and provided with such appurtenances as are common and necessary in continuous rolling-mills. In practice the dishing of the blank should begin after the first pass 20 and should be gradual, and may even advantageously begin with the first set of rolls A. The dishing or concaving may, however, begin with any set of rolls and continue either uniformly or by gradual increase until the 25 last set E has been reached. All the intermediate sets B C D will usually be shaped to dish or bend the blank laterally, and the conformation or shape of the rolls is adequately shown in Fig. 2, one of the rolls being circumferentially grooved, as shown at a, and the other correspondingly reinforced or flanged, as shown at a'.

It should be understood that I do not confine myself to any particular bend, dish, or other lateral deflection of the metal from a horizontal plane, but show the concave dishing or segmental shape merely as an illustration of the general idea or principle upon which my invention is based.

40 II I J designate, respectively, the planes, tables, or guides located between the sets of rolls and grooved longitudinally to receive and guide the metal from one set to another. These grooves are of a shape, width, and depth conformable to the curved or dished varying shape, width, and depth of the stock, and require no detailed description.

In rolling with the apparatus above described a fine fin or bead gradually gathers 50 or is formed on the edge of the blank, and this should be disposed of before the blank is finally straightened or flattened.

I make adequate provision for the reduction and obliteration of the fin by use of a 55 pair of rolls which may be located between the last reducing set and the flattening-rolls. The fin-reducing rolls are shown in Fig. 5, and consist of a plain roll G and a slightly-grooved roll II'. The groove L is rectangular and nearly equals in width the desired width of the finished product. The blank, being constructed laterally, by reason of its bend or deflected form easily enters the groove,

and by the compression or impact of the plane has its rough or finned edges forced into the 65 angles of the groove and the fin or bead compressed into the body of the blank or reduced to a condition conformable to the requirements of finish and good workmanship.

While I have shown and described the rolls 70 as having each a single pass-groove, it is obvious that the rolls may be grooved at intervals so as to form several separate and distinct grooves, and that the tables may be of suitable form and width so that several blanks 75 may be simultaneously reduced.

Having described my invention, what I claim, and desire to secure by Letters Patent, is—

1. A continuous rolling-mill for the production of hoop or strap metal, comprising several sets of reducing-rolls, of which two or more sets have their rolls respectively grooved and flanged, the grooves and flanges of one set being more abrupt than those of the preceding set and forming a pass of less depth, substantially as described. 80

2. A continuous rolling-mill for the production of hoop or strap metal, comprising a set of rolls intermediate in the train of which set 90 one roll is dished or grooved and the other flanged, whereby a concaving, corrugating, or deflecting pass is formed for the purpose of dishing, corrugating, or laterally deflecting the metal in its course, substantially as described. 95

3. In a continuous rolling-mill for the production of hoop or strap metal, the combination, with one or more sets of rolls intermediate in the train, of which one roll is grooved 100 or dished and the other correspondingly flanged, of a set of plain finishing-rolls terminating the train, substantially as described.

4. In a continuous rolling-mill for the production of hoop or strap metal, comprising 105 one or more sets of laterally-deflecting, dishing, or corrugating rolls and a set of plain finishing-rolls, a set of fin-reducing rolls located in advance of the finishing-rolls and comprising a plain roll G and a slightly-grooved roll 110 II, the groove L being of rectangular form, substantially as described.

5. In a continuous rolling-mill for the production of hoop or strap metal, the combination, with a train in which one or more sets have 115 dished or corrugated deflecting-passes, of the grooved tables or guides III, &c., located between the respective sets of rolls, substantially as described.

In testimony that I claim the foregoing I have hereunto set my hand this 25th day of March, 1889.

DAVID LARKIN.
